STARTING APPARATUS FOR INTERNAL
COMBUSTION ENGINESRichard Hammer, Winnenden, Germany, assignor
to Robert Bosch Gesellschaft mit beschränkter
Haftung, Stuttgart, GermanyApplication October 23, 1934, Serial No. 749,627
In Germany November 4, 1933

18 Claims. (Cl. 74—7)

The present invention relates to starting apparatus for internal combustion engines, in which the pinion is connected to the driving shaft by means of a friction clutch acting automatically through an axially movable pressure member and can be displaced longitudinally together with the driving shaft or relatively to it without substantial rotation relative thereto for engagement. The known starters of this kind have the disadvantage that the toothed rim of the flywheel and the pinion are damaged or at least greatly worn if the teeth of the pinion, on engagement, impact with the teeth of the flywheel, because when the teeth encounter each other the whole torque of the starter is transmitted to the pinion. In order to overcome this drawback, it has already been proposed in electric starters to provide an auxiliary field, which during the engagement of the pinion can only deliver a small torque, in addition to which, after the engagement of the pinion, the main field which exerts the full torque is put into circuit in dependence on the movement of the pinion. It has also been proposed to reverse the direction of rotation of the armature on the engagement of the pinion by the auxiliary field. These apparatus have the disadvantage that troublesome appliances are necessary to change over the field windings in dependence upon the position of the pinion.

In order to overcome all these disadvantages, according to the invention the pinion is connected to the starter shaft by a clutch for small torque for the engagement, and by a clutch for the full torque for starting up the motor.

Four examples of construction according to the invention are shown in the accompanying drawings, in which:

Figure 1 is a diagrammatic illustration of a starter.

Figure 2 is a second form of the invention in longitudinal section.

Figure 3 a section on the line 3—3 of Fig. 2.

Figure 4 a longitudinal section of a third method of carrying out the invention.

Figure 5 a section on the line 5—5 of Fig. 4.

In Figure 1, *a* is the armature of an electric motor, and *b* the armature shaft which is borne at *c* and *d*. On the armature shaft a sleeve *e* is arranged so as to be rotatable and axially displaceable. The end of the sleeve facing the bearing *d* is formed as a pinion *f* while the other end is provided with claws or clutch teeth *g*. The bore of the sleeve is enlarged at this latter end to receive a friction spring *h*, which at one end is fastened to the shaft of the arma-

ture and bears on the inside of the sleeve. *i* is a locking pin which is inserted in a radial hole of the sleeve and can engage in an annular groove *k* in the armature shaft. *m* is a spring which tends to draw the pin outwards.

Externally the pin bears on a fixed stop *n* connected, for instance, to the casing of the starter, and having two steps *o* and *p*, which are so arranged that in the position of rest of the starter the pin engages in the groove *k* of the armature shaft and in the contracted position is drawn out of the groove. On the armature shaft a friction clutch plate *q* is keyed. This has claws *r* which can engage with the claws *g* of the sleeve. *s* is a compression spring, which is arranged between the clutch plate *q* and the sleeve *e*, and *t* is the return spring of the armature.

The mode of action is as follows:—

When the starter is switched on for starting the motor, the rotating armature is attracted by the poles of the starter and thereby also the sleeve *e* displaced by the spring *s* and rotated by the slip spring *h*. If the pinion engages without impact, the pin *i* is drawn out of the groove *k* as soon as it comes below the step *p* of the stop *n*. On further displacement, the pinion sleeve abuts against the projection *u* of the bearing *d*. Since the armature can now move still further, the claws *r* on the clutch *q* come into engagement with the claws *g* of the sleeve. The armature shaft and the sleeve are now coupled together by the clutch *q*.

When the engine overtakes the starter, the armature is drawn back in known manner by the spring *t* and the sleeve pushed back by the driving pin *v*.

If tooth impacts on tooth, only the weak friction clutch formed by the spring *h* is operative. A coupling of the sleeve *e* with the clutch plate *q* is hindered by the locking pin *i*, which in this position of the sleeve still engages in the groove *k* of the armature shaft and thus locks the armature shaft relative to the sleeve. As soon as the pinion has run itself into the spaces between the teeth of the flywheel, the sleeve is unlocked, whereupon the further starting operation proceeds in the above described manner. The clutch for the full torque is thus cut in quite automatically.

A second method of carrying out the invention is shown in Figures 2 and 3. Here, *l* is the armature shaft of an electric motor *2*. On the armature shaft a sleeve *3* is arranged so as to be rotatable. The end of the sleeve situated at the

- end of the armature shaft is formed as a pinion 4, whilst at the other end of the sleeve a thread 5 is provided, on which a nut 6 can screw. This nut forms a part of a friction clutch 7, which is 5 to couple the armature shaft 1 with the sleeve 3. The counter-part to the nut 6 is a shell 8, keyed on to the armature shaft. Between the nut and this shell, friction discs 9 and 10 are arranged in the usual manner, which engage in 10 grooves 11 and 12 in the nut and the shell. 13 is a pressure plate for the friction discs, which plate 13 can bear against an abutment 14, and 15 is a flange of the nut 6 serving as pressure member of the clutch. One of the discs connected 15 with the shell, namely the disc 10a, has lugs 16 engaging in the grooves of the shell which are extended beyond the edge of the shell. On the casing 17 of the starter is provided an annular disc 18, which forms a stop for the lugs 16 of the 20 disc 10a and lies on the side of the lugs facing the pressure plate 13. In the flange 15 of the nut 6, small compression springs 19 are inserted which gently press those discs which lie between the flange and the annular disc against the latter. 25 In the position of rest of the starter the distance α of the pressure plate 13 from the friction discs is greater than the distance β of the pinion 4 from the toothed rim 20 of the flywheel of the internal combustion engine.
- 30 The mode of action of this apparatus is as follows:
- To start the internal combustion engine, the electric motor 2 is switched on. The armature of the motor is in known manner attracted into 35 the field of the motor, and thereby the pinion on the armature shaft moved towards the toothed rim of the engine. By this displacement of the armature the whole clutch 7 is likewise moved. The small springs 19 of the nut 6 press the friction discs steadily in the direction of the pressure plate 13 or annular disc 18, so that thus the discs do not follow the motion of the armature but the pressure plate 13 approaches nearer and nearer to the friction discs. When the pinion has 40 travelled the distance β , it begins to engage with the toothed rim 20. Since the distance β is smaller than the spacing α of the pressure plate from the friction discs, these cannot come into operation until the pinion has already to a certain 45 extent engaged in the toothed rim of the flywheel, i. e., the friction plates 9, 10 can only all come into action when the pinion teeth are already in mesh with the flywheel teeth. When the pinion is fully engaged, the pressure plate 13 has moved forward the friction discs so far that 50 the disc 10a no longer bears on the annular disc 18 and therefore all the discs can be compressed between the nut flange 15 and the pressure plate 13.
- 55 60 If however, pinion tooth impacts on flywheel tooth, which may occur after travelling the distance β , the pinion is held fast. The nut 6 is driven by the discs lying between the flange 15 and the annular disc 18 and screws itself towards 65 the discs. As in this position the pressure plate 13 does not yet bear on the friction plates, only the discs situated between the nut flange 15 and the annular disc 18 are pressed together. Since the torque transmitted by a friction disc clutch 70 is substantially proportional to the friction surfaces of the discs, the torque transmitted by the few discs—in the example illustrated two discs—is only small, so that an injury to the teeth of the pinion and flywheel is avoided. Here also the 75

change from low torque to high torque takes place automatically.

In the third example of construction, shown in Figures 4 and 5, in which the same references are adopted for the same parts as in Figures 2 and 3, the friction disc 25, which is preferably shaped like a pot, and bears on the flange disc 15 of the nut 6, is pressed by a spring 26 against the flange 15 of the pressure nut 6. The spring 26 bears against an abutment 27, which is provided on the coupling shell 8. The spring 26 is so chosen that its pressure is overcome by the attraction force of the armature, when the nut 6 bears against the bearing 28. In this case the pressure plate 13 is moved forward so far towards the friction discs, that it presses these against the flange of the nut 6, whereby all the said discs become operative, i. e., the full torque of the armature is transmitted.

If tooth impacts on tooth, only the friction between the flange 15 and the friction disc 25 is effective for the transmission of the torque from the armature to the pinion.

The starting apparatus according to the invention renders it possible to go to the full torque of the starter motor, before the pinion is engaged, without having to fear that in the engagement the pinion and the toothed rim of the flywheel will be damaged.

I declare that what I claim is:

1. Starting apparatus for internal combustion engines comprising a driving shaft, a pinion, driving means connected with said driving shaft and rotating the same before and after said pinion is in mesh with a toothed member of the engine, friction clutch means, in constant engagement, adapted to transmit only a low torque from said shaft to the pinion, friction clutch means adapted to transmit the full torque of the driving means to the pinion and means for always automatically bringing said second-mentioned clutch means into operation after the pinion is in mesh with the toothed member of the engine but preventing said second mentioned clutch means from coming into operation until the pinion is in mesh with said member.

2. Starting apparatus for internal combustion engines comprising a driving shaft, a pinion adapted to mesh with a toothed member of the engine to be started, driving means connected with said driving shaft and rotating the same before and after said pinion is in mesh with said toothed member, friction clutch means, in constant engagement between said driving shaft and said pinion and means permitting operation of a portion only of said clutch means to transmit a low torque only during meshing of the pinion with said toothed member and for bringing into operation the remainder of said clutch means only after meshing of the pinion.

3. Starting apparatus for internal combustion engines comprising a driving shaft, a pinion adapted to mesh with a toothed member of the engine to be started, driving means connected with said driving shaft and rotating the same before and after said pinion is in mesh with said toothed member, friction clutch means including friction discs, a portion of which are in constant engagement, between said driving shaft and said pinion and means permitting operation of a portion only of said friction discs to transmit a low torque only during meshing of the pinion with said toothed member and for bringing into operation the remainder of the friction discs only after meshing of the pinion.

4. Starting apparatus for internal combustion engines comprising a driving shaft, a pinion, driving means connected with said driving shaft, friction clutch means including friction discs between said driving shaft and pinion adapted to transmit the whole torque of the driving means to the pinion, pressure members at opposite ends of said friction discs and a fixed stop intermediate of said pressure members and means cooperating therewith and with said pressure members adapted to bring into operation a portion only of the friction discs during engagement of the pinion. 5
5. Starting apparatus for internal combustion engines comprising a driving shaft, a pinion, driving means connected with said driving shaft, friction clutch means including friction discs between said driving shaft and pinion adapted to transmit the whole torque of the driving means to the pinion, pressure members at opposite ends of said friction discs and a fixed stop intermediate of said pressure members and means cooperating therewith and with said pressure members adapted to bring into operation only those friction discs located between itself and one of said pressure members during engagement of the pinion. 10
6. Starting apparatus for internal combustion engines comprising a driving shaft, a pinion, driving means connected with said driving shaft, friction clutch means between said driving shaft and pinion including friction discs, a driving clutch member and a driven clutch member, one of said discs connected with the driving clutch member having a projection extending externally of the driving clutch member and a fixed stop adapted for engagement with said friction disc having said projection and means cooperating therewith to cause this disc alone to come into operation during engagement of the pinion. 15
7. Starting apparatus for internal combustion engines comprising a driving shaft, a pinion, driving means connected with said driving shaft, friction clutch means including friction discs between said driving shaft and pinion adapted to transmit the whole torque of the driving means to the pinion, pressure members at opposite ends of said friction discs, a fixed stop intermediate of said pressure members adapted to bring into operation only those friction discs located between itself and one of said pressure members during engagement of the pinion and springs between said pressure member and said discs for maintaining said discs in engagement with the stop during engagement of the pinion. 20
8. Starting apparatus for internal combustion engines comprising a driving shaft, a pinion, driving means connected with said driving shaft, friction clutch means between said driving shaft and said pinion including friction members associated with the driving shaft and the pinion respectively and means including opposed pressure members associated with the driving shaft and pinion respectively and a spring abutting at one end against one of said pressure members and abutting at the other end against one of the friction members associated with the driving shaft to press the same towards the other pressure member. 25
9. Starting apparatus for internal combustion engines comprising a driving shaft, a pinion, driving means connected with said driving shaft, friction clutch means between said driving shaft and said pinion including friction members associated with the driving shaft and the pinion respectively and means including opposed pressure members associated with the driving shaft and pinion respectively and a spring abutting at one end against one of said pressure members and abutting at the other end against one of the friction members associated with the driving shaft to press the same directly against the other pressure member. 30
10. Starting apparatus for internal combustion engines comprising a driving shaft, a pinion, driving means connected with said driving shaft, friction clutch means between said driving shaft and said pinion including friction members associated with the driving shaft and the pinion respectively and means including opposed pressure members associated with the driving shaft and pinion respectively and a spring abutting at one end against one of said pressure members and abutting at the other end against one of the friction members associated with the driving shaft to press the same directly against the other pressure member which is associated with the pinion. 35
11. Starting apparatus for internal combustion engines comprising a driving shaft, a pinion, driving means connected with said driving shaft and rotating the same before and after said pinion is in mesh with a toothed member of the engine, friction clutch means between said driving shaft and said pinion including friction discs associated with the driving shaft and the pinion respectively, resilient means for pressing certain of said friction discs together to transmit a low torque from the driving shaft to the pinion during engagement of the pinion and means including a pressure member for causing engagement of all of said discs to transmit a high torque after such engagement of the pinion and operable to always prevent engagement of all of said discs until the pinion is in mesh with said toothed member. 40
12. Starting apparatus for internal combustion engines comprising a driving shaft, means for driving said shaft, a pinion, a multiple-disc clutch between said driving shaft and pinion, and means including an automatically acting pressure member and an abutment cooperating therewith operable to permit engagement of only a portion of the clutch discs during engagement of the pinion and to permit engagement of all of the clutch discs after engagement of said pinion. 45
13. Starting apparatus for internal combustion engines comprising a driving shaft, a pinion, driving means connected with said driving shaft, friction clutch means including a portion substantially in engagement between said driving shaft and said pinion adapted to transmit only a low torque and means for maintaining a portion of said clutch means in all events inoperative while said driving shaft is rotating but until the pinion is in mesh with the toothed member of the engine. 50
14. Starting apparatus for internal combustion engines comprising a driving shaft, driving means connected with said driving shaft, a sleeve rotatably mounted on said driving shaft, a pinion secured against rotation on said sleeve and adapted to engage a member of the engine to be started, a control member mounted on said sleeve for longitudinal movement thereof and rotary movement therewith, and friction clutch means between said shaft and said control member comprising a high-torque friction clutch and a low-torque friction clutch, said control member controlling the operation of said high-torque clutch, 55
- 70
- 75

and means cooperating with said control member for preventing operation of said high-torque clutch until after engagement of said pinion with said engine.

5 15. Starting apparatus for internal combustion engines comprising a rotatable shaft mounted for longitudinal and rotary movements, driving means for imparting longitudinal and rotary movement to said shaft, a driving member rotatably mounted on said shaft and longitudinally movable therewith adapted to engage a member of the engine to be started, a control member mounted on said driving member for longitudinal movement thereof and rotary movement therewith, a high-torque friction clutch and a low-torque friction clutch between said shaft and said control member, said control member controlling the operation of said high-torque clutch, and means cooperating with said control member for preventing operation of said high-torque clutch until after engagement of said driving member with said engine.

16. Starting apparatus for internal combustion engines comprising a rotatable shaft mounted for longitudinal and rotary movements, driving means for imparting longitudinal and rotary movement to said shaft, a sleeve rotatably mounted on said shaft and longitudinally movable therewith, a pinion secured against rotation on said sleeve and adapted to mesh with a member of the engine to be started, a nut threaded upon said sleeve for longitudinal movement thereof and rotary movement therewith, a high-torque friction clutch and a low torque friction clutch between said shaft and said nut, said nut controlling the operation of said high-torque clutch, and means cooperating with said nut for preventing operation of said high-torque clutch until said pinion is in mesh with said engine member.

17. Starting apparatus for internal combustion engines comprising a rotatable shaft mounted for longitudinal and rotary movements, driving means for imparting longitudinal and rotary movement to said shaft, a driving member rotatably mounted on said shaft and longitudinally movable therewith adapted to engage a member of the engine to be started, a control member mounted on said driving member for longitudinal movement thereof and rotary movement therewith, a main friction clutch operatively interposed between said shaft and control member and tension controlled by the latter, a second friction clutch of less torque-transmitting capacity than said main clutch also interposed between said shaft and said control member, and means cooperating with said control member for preventing operation of said main clutch until after engagement of said driving member with said engine.

18. Starting apparatus for internal combustion engines comprising a rotatable shaft mounted for longitudinal and rotary movements, driving means for imparting longitudinal and rotary movement to said shaft, a driving member rotatably mounted on said shaft and longitudinally movable therewith adapted to engage a member of the engine to be started, a control member mounted on said driving member for longitudinal movement thereof and rotary movement therewith, friction clutch means between said shaft and said control member, and means cooperating with said control member for bringing a portion only of said clutch means into operation to transmit a low torque during engagement of said driving member with said engine and for bringing into operation the remainder of said clutch means after engagement of said driving member with the engine.

RICHARD HAMMER. 40
